LOOM CONSTRUCTION

Anna Fox, Yonkers, and Harry J. Dudley,
New York, N. Y.

Application June 15, 1944, Serial No. 540,482

5 Claims. (Cl. 139—34)

This invention relates to a loom and it consists in the constructions, arrangements and combinations herein described and claimed.

It is the cardinal object of the invention to provide a loom wherein a plurality of needles are employed for support of the warp in a manner to permit manual weaving of the weft under and over the needles in the production of any desired pattern.

It is also an object of the invention to provide a loom wherein a needle holder is employed for support of needles, the latter being operatively engaged with the warp to form sheds through which the weft may be readily passed, the needle holder being adjustable to vary the length of the shed openings.

More particularly, it is an object of the invention to provide a loom of simple construction, consisting of a base, an upright support upon which there is vertically adjustable a needle holder for support of needles at desired distances above the weaving position of the loom.

Additional objects, advantages and features of invention will be apparent from the following description, considered in conjunction with accompanying drawings, wherein

Figure 1 is a perspective view of the loom illustrating the needle holder in inoperative position.

Figure 2 is a fragmentary, perspective view illustrating the needle holder in operative position and illustrating the manner of forming the warp shed.

Figure 3 is an enlarged fragmentary top plan view of the loom.

Figure 4 is an enlarged fragmentary top plan view of the needle holder detached.

Figure 5 is a vertical section through the loom.

Figure 6 is an enlarged fragmentary section illustrating the mode of weaving.

There is illustrated a loom generally indicated by the reference character 10, consisting of a base 11 upon which there is secured an upright support 12. The support 12 may be of any desired height and may be of any approved exterior contour, but in the present instance, the support is shown as an oblong block.

A needle holder 13 is employed, consisting of an elongated block, having semi-circular end portions 14 and an elongated medial opening 15 of such dimensions as to freely receive the upright support therethrough. Spaced outwardly of the opening 15, a multiplicity of wells 16 are formed extending circumferentially about the opening 15, for support of respective needles 17.

A warp holder 18 is fixed upon the upper end of the support 12 by means of screws 19, and as shown, is of the same dimensions and end contour as the needle holder 13, although the holder 18 is formed with a raised central portion 20 of a width and length less than the body of the holder 18 forming an upstanding wall 21. The warp holder 18 is provided with a multiplicity of apertures 22, there being one in registry with each of the wells 16 for reception of the needles 17, the needles being of such length as to stop short of the upper edge of the apertures when the needle holder is in position shown in Figure 1.

Upon each end of the upright support 12, a series of vertically spaced openings 23 are formed adapted to receive a pin 24 for support of the needle holder 13 at desired vertical positions upon the upright support.

A series of warp holding pins 25 are mounted within the wall 21, a pair being provided for each aperture 22 disposed upon opposite sides thereof and extending at right angles to the wall 21.

Each of the needles 17 is formed at its upper end with a notch 26 within which the warp is to be positioned, as will be described hereinafter.

The operation of the loom is substantially as follows: From the position shown in Figure 1, the needle holder 13 is moved vertically upon the support 12 to a desired position and pins 24 are inserted in apertures 23 immediately below the holder 13 for support thereof. The needles 17 are thus moved through the apertures 22 to a distance above the warp holder 18, as may be seen in Figure 2. The warp 27 is anchored or suitably attached to respective pins 25 at opposite sides of respective needles 17 forming a shed 28 through which weft threads 29 may be manually threaded. Various colored weft threads may be employed to develop many attractive patterns, the threads being passed alternately from one side to the other of respective needles, in much the same fashion as followed in basket weaving.

Needles of different diameters may be employed, depending on the pattern it is desired to weave and therefore the wells 16 and apertures 22 must be of diameters to accommodate the largest needles to be employed in the loom.

It is not necessary that the loom be completely assembled with needles 17 since the number of needles involved will be in accordance with the article being woven. When the article has been woven, it is only necessary to remove the pins 24, allowing the holder 13 and associated needles to move to the position shown in Figure 1.

While we have shown and specifically described

the loom, this is by way of illustration only, and we consider as our own all such modifications in construction as fairly fall within the scope of the appended claims.

We claim:

1. In a loom, a base having an upright support, a warp holder on the top of the support, a needle holder vertically adjustable upon said support to present needles carried thereby above said warp holder, said needles being constructed for support of a warp thread, defining a shed through which weft threads may be inserted between said needles.

2. In a loom, a base having an upright support, a warp holder fixed to the top of the support, a needle holder consisting of an elongated member having a medial opening receiving said support therethrough, means for maintaining said needle holder in vertical adjustable positions upon said support, said needle holder further having means for vertical retention of spaced needles above said warp holder, said needles being constructed for support of a warp thread defining a shed through which weft threads may be inserted between said needles.

3. In a loom, an elongated rectangular base member, an oblong upright support fixed cen-

trally of the base, a warp holder fixed to the upper end of the support, a needle holder slidably mounted on said support consisting of an elongated member having a medial opening for reception of the upright support, and further having a plurality of wells circumferentially spaced, said warp holder having a plurality of circumferentially spaced openings aligned with respective wells, needles positioned in the wells and extended into aligned openings of the warp holder, means for holding the needle holder in a vertical adjusted position to present an upper portion of the needles above the warp holder, said needles being constructed for support of a warp thread defining a shed through which weft threads may be inserted between said needles.

4. The structure of claim 3 in which the means for holding the needle holder in an adjusted position consists of vertically spaced apertures formed in the upright support and a removable pin engaged in one of said apertures below said needle holder.

5. The structure of claim 3 in which the warp holder includes spaced pins for securement of the warp thread.

ANNA FOX.
HARRY J. DUDLEY.
